VARIABLE CONDENSER

Frank W. Godsey, Jr., North Adams, and Robert C. Sprague, Williamstown, Mass., assignors to Sprague Specialties Company, North Adams, Mass., a corporation of Massachusetts

Application September 3, 1935, Serial No. 39,020

2 Claims. (Cl. 175—41.5)

The present invention relates to variable condensers of the type as used for trimmer or padding condensers, antenna condensers, etc.

Condensers of this type have to meet various manufacturing and operating requirements. For instance, they must be small and compact, inexpensive, easily adjustable, and be so designed as to readily lend themselves to economical manufacture in mass production. In addition, they must be mechanically stable and return to the same capacitive setting after being subjected to a heat cycle. Furthermore, the adjustments must be simple and continuously variable throughout the rated capacity range of the condensers, and any obstacle interfering with a continuous adjustment, such as binding of the elements or of the adjusting means, undue friction, and the like, is to be avoided.

Such condensers usually consist of at least one fixed and at least one flexible and adjustable metal condenser plate, between which metal plates is disposed a plate or layer of dielectric material, for example of mica. To obtain a continuous variation of the capacity by manual adjustment, the flexible plate is made of resilient material having a high degree of elasticity, and its capacitive relationship to the fixed plate is varied by flexing it toward or away from the fixed plate by means of adjusting screws, nuts or the like.

The main difficulty heretofore encountered with this type of condensers, was due to a sidewise displacement of the flexible plate relative to the fixed plate, and/or a binding of the condenser plates and dielectric plates, due to inadequacy of the mounting and adjusting means, and especially due to a lack or inadequacy of the guiding means.

Such a relative displacement of the condenser plates or their binding was not only brought about in prior art condensers when the adjustment of the condenser was changed, but also took place with a set adjustment, due to the successive expansions and contractions of the condenser plates, as a result of the heat cycle which the condensers undergo in use; this because the condensers are used as a rule in devices, for example in radio receiving sets, in which a considerable heat development takes place during operation, so that even if the heat development in the condenser per se is negligible, it heats up because of the heat developed in the radio set. Such heating up causes an expansion of the condenser plates, and when the radio set is placed out of operation and the condenser cools down, a cor-

responding contraction of the plates takes place.

To overcome some of these difficulties constructions have been suggested in which the end portions of the flexible condenser plates were riveted to the base. This expedient besides considerably increasing the size of the condenser—as much of the total area of the plates merely serves for their anchoring without adding to the effective capacity of the condenser—permits the plates to expand only in one and not in two directions, as a result of which strains are set up during the heating and cooling cycle, which cause the buckling of the plates and may also result in other mechanical defects.

To permit the plates to have relatively free expansion and contraction in both directions, constructions were suggested which limited the freedom of the condenser plates merely by guides placed sidewise to the plates. Such guides as a rule are expensive and necessitate the use of excessive material.

It is the object of our invention to eliminate the above referred to difficulties, and to provide a condenser, which for a given capacity value, is more compact and requires less material than the prior art condensers.

Another object of the invention is to provide for guiding means of the condenser plates, which provide merely the three guiding points theoretically required for the proper location of one body with respect to another.

Another object of the invention is to combine two condensers into a single unit with novel adjusting means permitting individual adjustment of either condenser from the same side of the unit.

A further object of our invention is to eliminate objectionable capacitive coupling in a multiple condenser structure.

Further objects and advantages of our invention will appear as the specification progresses.

In the drawings forming part of this specification,

Figure 1 is a plan view of one embodiment of our invention;

Fig. 2 is a cross-sectional elevation along lines 2—2 of Figure 1;

Fig. 3 is a cross-sectional elevation of a twin or dual condenser made in accordance with our invention;

Figs. 4 and 5 are plan views of a condenser plate and of an insulator plate respectively, used in connection with the condensers shown in Figs. 1-3;

Fig. 6 is a side elevation of the dual condenser of Fig. 3;

Fig. 7 is a fractional bottom view of the condenser of Figs. 3 and 6.

Fig. 8 is a partial vertical sectional view showing a variation in the adjusting means of the condenser of Figs. 3 and 6;

Fig. 9 is a plan view of another form of condenser, in accordance with our invention;

10 Fig. 10 is a vertical section taken on the lines 10—10 of Fig. 9;

Fig. 11 is a plan view of still another form of condenser, in accordance with our invention.

15 Fig. 12 is a vertical section on the lines 12—12 of Fig. 11.

Referring to Figs. 1 and 2, a molded base 10 of insulating material such as artificial resin or the like, having rounded corners 11, is provided on its top with an open-ended shallow recess, between the side walls 18 of which is placed a condenser assembly A, later more fully described, and has on its two sides upwardly-projecting integral mounting lugs 12—12 having holes 13—13 to receive suitable attachment bolts.

20 Fig. 5 A central hole 14 of the base 10 is adapted to receive a slotted-end screw 15, which screw projects upwardly above the top face 16 of the base 10 and passes through the condenser assembly A. The screw 15 with a nut 17 forms the adjusting means for the condenser. Inwardly from the lugs 12—12 extend rounded guide ribs 20—20, which are preferably integrally molded with the base 10. The ribs 20—20 serve to locate the condenser assembly A and to guide the flexible plate 25 of the assembly.

25 It will be noted that the ribs 20—20 are disposed on opposite ends of the short axis of the condenser assembly A and contact with parts thereof along a semicircle of small radius.

30 Fig. 4 The condenser assembly A consists of two metallic condenser plates 25 and 25' (see Fig. 4) of identical shape except that plate 25 is flat, whereas plate 25' is concave downward. The plate 25' is of highly resilient spring material, 35 for example phosphor bronze, whereas plate 25 may be of the same material, but may also be of non-resilient material.

35 The plates 25 and 25' are provided with central clearance holes 26 and 26' respectively—50 which are sufficiently large to permit noncontacting passage of screw 15—and also with extending integral and inclined connection lugs 27 and 27' respectively. The plates 25 and 25' furthermore are provided with two rounded end 55 notches 29 and 30, and 29' and 30' respectively. The notches 30 and 30' are of a size to fittingly surround the ribs 20—20, whereas notches 29 and 29' are larger so as not to engage the ribs 20—20 when the plates 25 and 25' are mounted on the 60 base.

65 When assembling the condenser the plates 25 and 25' are placed with identical faces turned toward each other, i. e., with lugs 27 and 27' on opposite sides and with notches 29 and 30' and 70 notches 29' and 30 respectively on the same side of the assembly.

75 A thin plate 35 (see Fig. 5) of dielectric material, for instance mica, and having a slightly greater length and width than metal plates 25 and 25', is interposed between plates 25 and 25'. The dielectric plate 35 is provided with two identical notches 37—37 adapted to snugly engage the ribs 20—20, and with a central hole 36 which is smaller than holes 26 and 26'. In the assembled condenser, the hole 36 and slots 31—37 of

plate 35 register with the hole 14 and the ribs 20—20 respectively.

It will be noted from Fig. 1 that in the assembled condenser one of the metal plates, for example the flat plate 25, engages with its notch 30 the corresponding left-hand rib 20, whereby its left-hand edge 98 falls at a distance L from the left-hand wall 18 of base 10; whereas the right-hand edge 99 contacts with the right side wall 18. Thus, when plate 25 is expanded by 10 heat, it can freely expand in both length and width directions, whereas at the same time it is securely guided at the three theoretically required points; two such points being provided by its right side edge 99 bearing against side wall 15 18, and the third point being afforded by the semicircle contact between notch 30 and the left-hand rib 20. To be able to freely expand in all directions there must be a slight clearance between the end rib 20 and notch 30.

20 The insulating plate 35 is placed on top of plate 25 and extends substantially from one side wall 18 to the other side wall 18, and also extends beyond both ends of plates 25 and 25'.

The vaulted and adjustable plate 25' lies with 25 its left-hand edge 98' close to the left-hand wall 18, whereas its right-hand edge 99' is spaced from the right side wall 18, and its notch 30' engages the right-hand rib 20 in a manner similar to that of plate 25.

30 It will be also noted that the inclined extension lugs 27 and 27' extend at the same end, but at opposite sides of the assembly.

On top of the flexible plate 25' there is provided a concave spring washer 40, by which a 35 uniform pressure can be exerted on the assembly A under action of nut 17.

The adjustment of the condenser depends on the position of nut 17, and by exerting a greater or smaller pressure on plate 25' this plate is flexed 40 to a greater or lesser amount and thereby accordingly changes its capacitive relation to the fixed plate 25.

Figs. 3 and 6 illustrate a twin condenser according to our invention in which two individual 45 adjustable condenser assemblies B and B' are mounted on a common base 50 and are independently adjustable from the same side. The upper portion of the base 50, which receives assembly B, is substantially identical with the base 50 10 shown in Fig. 2; the base 50, however, extends downwardly and is provided with an open-ended recess having side walls 18—18', ribs 20—20', and downwardly-extending mounting lugs 12—12'. The condenser assemblies B and B' are 55 placed within the recesses formed on the upper and lower portion of the base 50, in the same manner as has been described in connection with condenser assembly A of Figs. 1 and 2.

60 For the individual adjustment of the two condensers there are provided adjusting means which comprise a metallic bushing 51 having at the lower end two preferably knurled annular flanges molded into the middle portion of the base 50. The bushing 51 extends upwardly beyond the 65 base 50 and is provided with internal and external threads.

65 Against the bottom face of the condenser assembly B' lies a washer 56 (see Fig. 7) of insulating material having a substantially elliptical 70 contour; a flat bearing face, and a conical face. The washer 56 is provided with a central counterbored hole 100 and with two notches 58—58 provided at the two ends of its long axis. Into the counterbore of hole 100 fits the head 51 of a 75

bolt 55, which is provided at its upper end with a slot 65 and engages the internal threads of bushing 51. The notches 58—58 engage the lower ribs 20—20', and thereby fixedly hold the washer 56 against rotation. A nut 54 engages the external threads of bushing 51 and presses against the spring washer 40.

The adjustment of the upper condenser assembly B is effected in a manner similar to that explained in connection with Fig. 1 by turning the nut 54. Adjustment of the capacity of the lower condenser assembly B' takes place by moving the bolt 55 along the internal threads of bushing 51 using slot 65.

It will be thus noted that the capacities of the two condenser assemblies B and B', can be adjusted independently, and that both adjustments can be effected from the same side of the unit, which is especially desirable when the condenser is mounted on a panel or in an inaccessible place.

A variation of the adjusting means shown in Figs. 1, 3, and 6 is shown in Fig. 8, wherein a metallic insert 60 is rigidly molded in the insulating base 50 of the condenser, and is provided with an externally-threaded extension 61. The extension 61 is provided with a smooth inner bore adapted to snugly receive a bolt 62 recessed into the washer 56 to prevent turning, and extending upwardly through same and beyond the top of the extension 61 to receive an adjusting nut 63.

In the construction shown in Fig. 8 adjustment of the lower condenser B' is effected by turning the nut 63 against the upper end of extension 61, whereby condenser B' is to a greater or lesser extent compressed. Condenser B is adjusted by turning nut 54—adapted to fit the external threads of extension 61—whereby pressure is transmitted through the concave washer 40 to the condenser assembly B.

Referring to Figs. 9 and 10, a molded base 120 of a suitable vitreous insulating material and having parallel faces 68 and 69 and rounded corners 66 is provided with three mounting holes 67 located on one central axis thereof. On either side of the central axis are disposed identical condenser assemblies C—C later to be more fully described.

The face 68 is provided with two identical depressions 70—70 having octagonal cross sections arranged with their longer axes parallel to the axis of the holes 67—67. The depressions connect along their respective outer side with openings 71—71 and with indentations 72—72 along their inner sides; openings 71—71 and indentations 72—72 extending in the same direction as the depressions 70—70 which also connect at both ends with molded channels 73—73 extending through the base 120.

The base 120 is also provided with two similar internally-threaded metallic inserts 74 (only one of which is shown), having hexagonal heads 75 recessed in corresponding indentations 76 in the face 69 and having their upper ends crimped, as indicated at 77 upon cushioning washers 78 centrally located in recesses 79 in the bottom of the depressions 70. The washers 78 may be omitted if the base 120 is made of bakelite or similar type of molded plastics, but are used when the base is of vitreous material, for example, porcelain or the like.

The condenser assemblies C—C (only one of which is shown in section in Fig. 10) comprise a lower metal plate 80 and an upper metal plate 90 separated by a thin insulator 86. The plate 80 is substantially octagonal in shape and is nar-

rower in width than the depressions 70 into which it fits. One end of the plate 80 is provided with an extension or terminal lug 81, which passes slopingly downwards through the channel 73, whereas the other end of the plate 80 falls short of the opposite end of depressions 70.

The short oblique edges of plate 80 (see Fig. 9) are so proportioned as to guide the plate in the depressions 70 by the matching oblique sides 83 thereof. A central clearance hole 84 within plate 80 permits the passage of an adjusting screw 85 therethrough.

Plates 90, which are similar in size and shape to the plate 80, are provided with lugs 91 passing slopingly down through the right-hand channels 73. The plates 90, which are of heavy and resilient material, for instance phosphorus bronze, are concave downwards and are also provided with central clearance holes 92 for the passage therethrough of the adjusting screw 85.

The thin octagonal-shaped pieces 86 of mica or other insulating material which separate the plates 80 and 90, have a greater width and length than do the plates 80 and 90 and extend longitudinally to the ends of the depressions 70—70 and laterally into the openings 71—71 and indentations 72—72, whereby the plates 80 and 90 are effectually insulated from one another. The insulating pieces 86 are each provided with a central hole 88, of smaller diameter than that of the holes 84 and 92, whereas oblique sides closely fit the matching oblique sides of the depressions and are fixed thereby.

A circular washer 95 of bakelite or other insulating material, and a thicker metallic washer 96 of similar size and shape are placed over the upper plate 80 in the order given; the latter washer bearing against the under side of the head of the adjusting screw 85 which extends through the holes of washers 95 and 96 and into the threaded portion of the insert 74. Rotation of screw 85 changes the capacitive adjustment of the condenser by decreasing or increasing the flexure of the upper metallic plate 90.

Figures 11 and 12 illustrate a form of construction adapted to multiple condensers; only one unit being shown here. In the form shown in these figures the base 115, which is of metal, acts as a fixed plate for condenser D, and is provided with upturned edges 116, one of which is extended to form a mounting and terminal lug 117.

The condenser unit, later to be more fully described, is rectangular in shape and is guided on three sides by the upturned edges 116, while the fourth side is guided by two tabs 118 pressed upwards from the bases 115, which tabs also serve to guide one side of an adjacent unit (not shown).

The upper plate 105 is rectangular in shape and has a narrow downwardly-bent terminal lug 106; the base 115 and one side 116 being cut away in Fig. 12 at 110 to more clearly show this.

As shown in Fig. 12, the upper plate 105 is completely compressed, but in its free condition this plate is concave downwards in the direction of its long axis. A thin rectangular-shaped separator 107 of mica or other insulating material (as seen in place in Fig. 12), separates the base 115 and the plate 105, and overlaps all edges of the plate 105.

An upper insulating plate 111 of the same size and shape as the separator 107, but of greater thickness, is placed over the plate 105 and transmits the pressure of the adjusting screw 112 to the flexed plate 105; plates 105, 107 and 111 being each provided with central clearance holes, per-

mitting the noncontacting passage of the screw 112 therethrough and onto cooperating threads in the base 115.

The plate 111 is of such length that it substantially fills the space between the upturned edges 116, and is provided on its shorter sides with slots 109 adapted to receive upturned extensions 108 of the plate 105, which extensions terminate below the top surface of plate 111 when assembled, and whereby the plate 105 is effectively guided.

We have found that in past constructions in which two condenser assemblies were mounted on a common base, a capacitive intercoupling occurred between the two condensers due to the metallic parts of the adjusting means.

This drawback is eliminated in our construction by making the bolt 55 (see Fig. 3) of insulating material, or by so dimensioning the metallic parts of the adjusting means that the capacitive effect of the third condenser so formed remains below objectionable values. As a rule it is sufficient if the capacity of this third condenser does not exceed 2% of the capacity of the condensers of assemblies B and B'.

While we have described our invention on hand of specific examples and in specific applications, we do not wish to be limited thereto, but desire the appended claims to be construed as broadly as permissible in view of the prior art.

What we claim is:

1. In an adjustable condenser, a base of insulating material provided with a lateral recess open at the ends, each side wall of said recess being provided with an inwardly-projecting rib, a condenser plate provided on one side edge with a small notch and on its opposite edge with a larger notch, said plate being disposed in said recess with the larger notch clearing one of said ribs and with the corresponding edge in contact with the side wall, the opposite edge of the plate being spacedly located from the opposite side wall with the small notch fittingly engaging the corresponding rib.

2. In an adjustable condenser, a base of insulating material provided with a recess having two opposite side walls each provided with an inwardly-projecting rib, a condenser plate provided on one side edge with a small notch and on its opposite edge with a larger notch, said plate being disposed in said recess with the larger notch clearing one of the said ribs and with the corresponding edge contacting the side wall, the opposite edge of the plate being spaced from the opposite side wall with the small notch fittingly engaging the corresponding rib.

FRANK W. GODSEY, JR.
ROBERT C. SPRAGUE.
